UNITED STATES PATENT OFFICE.

MURRY BUTLER, OF BROOKHAVEN, MISSISSIPPI.

DESIGN FOR A BOOK-TABLE.

50,122.

Specification for Design.

Patented Jan. 2, 1917.

Application filed October 20, 1916. Serial No. 126,801. Term of patent 14 years.

To all whom it may concern:

Be it known that I, MURRY BUTLER, a citizen of the United States, residing at Brookhaven, in the county of Lincoln and State of Mississippi, have invented a new, original, and ornamental Design for Book-Tables, of which the following is a specification, reference being had to the accompanying drawing, forming part thereof.

Figure 1 is a perspective view of the book

table, showing my new design, and Fig. 2 is a front elevation of the book table, showing my new design.

I claim:

The ornamental design for a book table, as shown.

MURRY BUTLER.

Witnesses:

H. B. LEGGITTE,
W. A. CAMERON.
